UNITED STATES PATENT OFFICE.

ANTHONY FODOR, OF BUDAPEST, AUSTRIA-HUNGARY.

APPARATUS FOR CONNECTING CONDUCTING AND OTHER WIRES.

No. 902,389.

Specification of Letters Patent.

Patented Oct. 27, 1908.

Application filed November 14, 1907. Serial No. 402,222.

To all whom it may concern:

Be it known that I, ANTHONY FODOR, subject of the King of Hungary, residing at Rökksszilárd-utea 20, Budapest, Kingdom of Austria-Hungary, have invented certain new and useful Apparatus for Connecting Conducting and other Wires, of which the following is a description.

This invention relates to improvements in mechanism for twisting lapped wires to join the same of that class wherein devices are provided for holding the lapped wires and wherein devices are also provided for twisting the wires held by said first mentioned devices.

One of the objects of my invention is to provide a device of this general character which will permit of the twisting of the lapped wires in opposite directions or in one direction and in connection with the last mentioned utility of the invention a special feature consists in independently and removably mounting the twisting and holding devices so that the same may be adjusted with respect to each other in a manner to effectively hold one end of the lap to be twisted and to engage with the twisting device the other end of the lap.

A further feature of novelty consists in the provision of holding devices so constructed that they will yield during the twisting and resultant shortening of the lapped wires.

Other features of novelty will be more fully described in connection with the accompanying drawing and will be more particularly pointed out in and by the appended claims.

In the drawing:—Figure 1, is a view in elevation of two lapped wires inclosed by a tube illustrating the appearance of the same before the twisting operation. Fig. 2, is a similar view showing the parts twisted in one direction. Fig. 3, is a similar view showing the parts twisted in opposite directions. Fig. 4, is a side elevation, partly in section, of my improved twisting mechanism. Fig. 5, is a sectional view thereof on line *a*—*b* of Fig. 4. Fig. 6, is a side elevation, partly in section, of one of the holding devices detached from the remainder of the mechanism shown in Fig. 4. Fig. 7, is a sectional view on line *a'*—*b'* of Fig. 6. Fig. 8, is a detail view in side elevation of a portion of the twisting device. Fig. 9, is a plan view thereof.

First referring to Figs. 1 to 3 inclusive, 1

and 2 designate two lapped wires which may if desired be inclosed by a metallic tube 3. Fig. 2, illustrates the appearance of the part shown in Fig. 1, after the wires and the tube have been twisted in one direction for the purpose of uniting said wires. Fig. 3, illustrates the appearance of the parts when united by being twisted in opposite directions. After the twisting operation has been completed the projecting ends of the lapped wires may be bent backwardly upon the tube 3, as shown.

Next referring to my improved mechanism as illustrated in Figs. 4 to 9 inclusive a mounting is provided in the form of a bar 4, on which the coöperating twisting and holding devices are disposed. There is shown two holding devices which are movably or adjustably mounted on said bar and which are provided with means in the form of thumb screws 7 and 8 for locking said holding devices in their adjusted positions. Each of said holding devices consist of standards 5 and 6, provided with openings in their lower portions for receiving the bar 4. At their upper ends said devices are provided with means for gripping the wires and as shown said means consist of jaws 9 and 10 which are pivotally united at 14 and are normally held apart from each other by springs 37 interposed between said jaws and seated in suitable recesses formed therein as clearly shown in Fig. 6. The lower jaws 10 are apertured at 13 to receive the upper reduced ends of the standards 5 and 6 and screws 15 are inserted in said standards and are provided with heads 16 adapted to engage the lower jaws 10 to retain the same upon said standards. This construction constitutes a pivotal mounting of the jaws and permits them to swing or turn to compensate for shortening of the lapped wires as the result of the twisting operation. Means are provided for clamping the jaws 9 and 10 upon the wires and as shown said means consists of a threaded bolt 11 provided with a winged head 15'. Said bolt 11 has threaded engagement with the lower jaw 10 and passes freely through an opening in the upper jaw 9 as will be clearly seen by reference to Fig. 6.

Next referring to the twisting device the same consists, as shown, of a sleeve 24' mounted upon the rod 4 and provided with a handle 24 by means of which the device may be adjusted on its mounting independently of the holding devices and toward or

from the same. Said sleeve is provided with a bracket arm 24" in which bearings 19 and 20 are formed to receive a shaft 22. A worm 21 is mounted on said shaft and is operated 5 by a crank 23. Said sleeve 24' is provided with an upright 16' terminating in a hub 17 which is laterally slotted as clearly shown in dotted lines in Fig. 5, to permit insertion of the lapped wires. A sleeve 26 is rotatively 10 disposed in said hub and is provided on one end with a worm wheel 25 adapted to mesh with the worm 21 and be operated thereby. A nut 27 holds the sleeve in place in said hub. Said worm wheel 25 and sleeve 26 are slotted 15 at 36 so that when such slotted portion registers with the slot in the hub 17 the lapped wires can be inserted and it will also be understood that the nut 27 is slotted for the same purpose. In order to firmly grip the wires 20 at the twisting point jaws 29 and 31 are provided and the same are pivotally united with each other at 30 and are normally held apart from each other by a spring 32. The lower jaw 29 is rigidly secured to the worm wheel 25 and the upper jaw 31 is freely movable. A screw 33 has threaded engagement with the lower jaw 29 and passes freely through jaw 31 and is operated by a rod 35 slidably 25 mounted in a head 34 and operated in a well known manner.

It will be readily seen from the foregoing that a unitary mechanism comprising independently operable and removably mounted devices is provided which is adapted to 35 twist lapped wires in one direction or in opposite directions. If it is desired to unite two wires in the manner shown in Fig. 3, the twisting device is adjusted to bring the jaws 29 and 31 to an intermediate position between the holding devices and after the holding 40 and twisting devices have been secured to the wires the crank 23 is operated to effect the twisting operation shown. As the wires shorten the pivotal mountings of the jaws 9 and 10 permit the same to turn and approach 45 the twisting device. It will be seen that the holding devices are independently adjustable toward and from the twisting device and therefore the mechanism is readily adapted 50 to accommodate a lapped joint of any probable length.

If it is desired to twist a joint in one direction as shown in Fig. 2, one of the holding devices can be removed and the twisting device 55 can be adjusted to the free extremity of the lapped joint opposite that extremity engaged by the remaining holding device.

I claim:—

1. A mechanism for twisting lapped wires 60 comprising in combination, a bar, wire holding devices removably and adjustably mount-

ed on said bar and provided with means for locking said devices in their adjusted positions on said bar, and a device for twisting the lapped wires disposed between said 65 holders.

2. A mechanism for twisting lapped wires comprising in combination, a bar, wire holding devices removably and adjustably mounted on said bar and adapted to hold one or 70 both ends of a lapped joint of wire, said devices being provided with means for locking the same in their adjusted positions on said bar, and a device for twisting the lapped joint movably mounted on said bar and adapted 75 to grip the joint centrally and form a right and left hand twist when both of said holding devices are employed, said twisting-device serving when one of said holders is employed to grip one end of said joint and twist the 80 wires in one direction.

3. A mechanism for twisting lapped wires to join the same comprising in combination, a device for twisting said wires and adapted to engage the same at a central point, and 85 pivotally mounted holders adapted to engage the ends of the lapped wires, the pivotal mountings of said holders permitting the same to turn to compensate for the shortening of the wires as the same are being 90 twisted.

4. A mechanism for twisting lapped wires to join the same comprising in combination, a device for twisting said wires and adapted to engage the same at one end of the lapped 95 joint, and a pivotally mounted holder adapted to engage the wires at the other end of the joint, the pivotal mounting of the holder permitting the same to turn to compensate for the shortening of the wires as the same are 100 being twisted.

5. A mechanism for twisting lapped wires comprising in combination, a wire holding device, a wire twisting device co-operating therewith, means on which said holding and 105 twisting devices are independently adjustable, and means for locking said holding device in adjusted positions.

6. A mechanism for twisting lapped wires to join the same comprising in combination, 110 a wire holding device adapted to be moved by the wires as the same shorten, a device for twisting said wires, a mounting for said devices on which the same are independently adjustable, and means for locking said holding device in its adjusted positions.

In testimony whereof I affix my signature in the presence of two witnesses.

ANTHONY FODOR.
